CLAIM

The ornamental design for activity surface and rest apparatus, as shown and described.

DESCRIPTION

FIG. 1 is a top plan view of activity surface and rest apparatus showing our new design.

FIG. 2 is a rear elevational view thereof.

FIG. 3 is a bottom plan view thereof.

FIG. 4 is a front elevational view thereof.

FIG. 5 is a left side elevational view thereof.

FIG. 6 is a right side elevational view thereof; and,

FIG. 7 is a top perspective view thereof.
